UNITED STATES PATENT OFFICE.

LEO J. DU MAIS AND FLOYD E. MINER, OF CHICAGO, ILLINOIS, ASSIGNEES TO CHICAGO SHOE MACHINERY COMPANY, OF CHICAGO, ILLINOIS, A CORPORATION OF ILLINOIS.

THREAD-LOOPING MECHANISM FOR STITCHING MACHINES.

Application filed January 22, 1924. Serial No. 687,862.

To all whom it may concern:

Be it known that we, LEO J. DU MAIS and FLOYD E. MINER, citizens of the United States, and residents of Chicago, in the county of Cook and State of Illinois, have invented certain new and useful Improvements in Thread-Looping Mechanism for Stitching Machines, of which the following is a specification, reference being had to the accompanying drawings, forming a part thereof.

Broadly speaking, the purpose of this invention is to provide new and novel means of looping the thread in the path of the needle of a stitching machine and particularly, of such a machine used for stitching leather, and it consists in the features and elements and their combination hereinafter described, shown in the drawings and pointed out by the claim.

In the drawings:

Figure 1 is a side view of a stitching machine taken transaxially of the driving shaft and in a plane parallel to the path of the needle and certain other parts associated therewith which are directly concerned in and with the present invention.

Fig. 2 is a view taken as indicated at the line 2—2 on Fig. 1.

Fig. 3 is a fragmental view in plan, on an exaggerated scale of the thread looper, the thread hook and the needle.

Fig. 4 is a developed view of one of the cams.

Fig. 5 is a diagrammatic view in plan of the thread looper arm and indicating the path of travel of the thread looper eye.

It will be understood that in Figs. 1 and 2 of the drawings, only such parts as are concerned with the control of the lower one of a two-thread stitching machine are shown, omitting other parts which cooperate therewith in a manner well understood in the art, but which are not here sought to be claimed. The structure herewith shown comprises a base member 10, a bracket arm 11 and the two standards 12—12 which are suitably secured to the upper side of the base member. A shaft 13 is journaled in the bracket 11 and is driven in any suitable manner not here shown. Mounted on the shaft 13 and keyed thereto for rotation therewith is a compound cam 14 which ro-

tates in a counter-clockwise direction as indicated by the drawing.

The cam 14 has several sets of grooves, one set being cut or formed in the periphery thereof at 15, another in one of its lateral faces at 16, a third in the same face but nearer the center thereof at 17, and a fourth in the opposite face thereof at 18, shown in dotted lines, the latter road or groove governing the travel of a thread engaging needle which operates in a manner quite common to all machines, this cam road only being shown here to indicate the possibility of forming all the controlling roads or grooves for the said moving parts in a single cam wheel with the advantage of lightening the entire structure, minimizing the necessary power to operate the machine and with the further advantage of insuring that their predetermined relative position will remain unchanged, it being conceivable that several separate cams could and might, through inadvertence, become deranged.

The first two mentioned cam roads 15 and 16 control the action of a thread looping device 19, while the cam road 17 controls the action of a thread hook indicated at 20.

The thread looper 19 is mounted for traveling in a horizontal plane and has imparted thereto differential movement in a peculiar three-cornered orbit 21, (see Fig. 5) because of its being secured at the free end 22 of a bar 23 which is mounted for reciprocation in guides 25—25; the guides themselves being moved laterally through their connections 26—26 to a bar 27 which is fulcrumed at 28 to the base plate 10. A cam-engaging roller 29 is rigidly secured to the bar 27 some distance from the fulcrum 28 and motion is imparted by the cam road 15 in the periphery of the wheel 14. This cam road 15 it will be observed is formed to cause the thread looper to travel laterally, toward and from the thread hook 20. During this lateral movement caused by the bar 27 being swung about its fulcrum 28, a second movement is imparted thereto by the reciprocation of the bar 23.

The bar 23 which, as stated, is mounted in the guides 25—25 has connection, through a swivel joint 30, to a lever 31. This lever 31 is fulcrumed at 32 in the bracket 11. A conveniently arranged arm 32^a integral with

the lever 31 carries a roller 33 which engages the cam road 16; the total length of the lever arm 31 and the position or location of the roller 33 thereon provides the necessary longitudinal movement to the bar 23 by virtue of the shape or formation of the road 16 with which the roller 33 cooperates.

Further elucidating, it may be here stated that the several critical relative positions of these two last mentioned cam roads, 15 and 16 with their cooperating rollers 29 and 33 respectively, are indicated in Fig. 1 by the characters disposed successively around the wheel 14; these characters A to H inclusive, 15 and A¹ to H¹ inclusive, correspond to the characters in Fig. 5, which designate the position of the thread looper 19; that is when the parts are in the position shown in Fig. 1, the roller 29 occupies the position marked A. The roller 33 occupies the position A¹. The thread looper will then be in the position or point of the angle (see Fig. 5) indicated at A; upon rotation of the wheel 14 in the direction of the arrow, the next indicated position will be when the roller 29 is at B and the roller 33 is at B¹ and so on through the cycle, the thread looper will then travel, as indicated in Fig. 5 from A to B; dwell from B to C; travel from C to D; dwell from D to E; travel from E to F; travel from F to G; and back to H.

On one of the standards 12 is mounted a rock-shaft 40 which is actuated by the arm 41 having a roller 42 traveling in the road 17 of the wheel 14. The rock shaft 40 has mounted upon it for swinging, a lever 43 whose free end engages and operates the thread hook 20, which is mounted for longitudinal travel toward and from the path of the thread, said thread being conveyed in its path by the thread looper 19. It will be clearly understood by reference to Fig. 1 of the drawing that the thread hook 20 is mounted on the inner surface of the upwardly and forwardly extended portion of one of the standards 12 in an upwardly and rearwardly inclined guide-way and that the upper end of the lever 43 loosely engages a recess in the lower surface of said hook, to the end, when the lever 43 is rocked, the thread hook 20 will be slid back and forth in its inclined guide-way.

During the interval that the hook 20 is thrust outwardly and downwardly by an upward movement of the roller 42 to about the dotted line position in Fig. 3, and held there for approximately 170 degrees of travel of the wheel 14, the thread looper will assume

the position indicated at "D—E" (see Fig. 60 5); dwelling there until the said roller drops in the greater radius of the road 17 causing the hook 20 to engage the thread, and hold it in said position, the needle 50 having previously descended under action of the segment 51 and quadrant 52, through the slot 53 in the work plate 54. The thread looper then traveling across the needle, passing from the position E to F, and finally to G, pulling the thread taut. 70

It is to be understood that the needle 50 in descending, enters the work through a hole in the work which was produced by an awl 60 a fragment of which is shown in Fig. 1. This awl is mounted upon a quadrant shown 75 61 and operating from the under side of the work plate 54. The awl quadrant 61 is operated by a segment 62 and controlled by the cam road 18 on the wheel 14.

While the thread is so engaged by the 80 hook 20, the needle 50 is caused to recede and as its barb 55 engages the thread for drawing it through the slot 53 and also the work, the hook 20 is again advanced ready for the next stitch. The thread so drawn up through the work by the needle, forms a loop for the reception of a bobbin in a customary and well known manner, not here shown or claimed. 85

Having thus fully described our invention, 90 what we claim as new and desire to secure by Letters Patent is:

In a stitching machine, the combination with a barbed needle and the work-plate, said work-plate having a slot for the passage 95 of the needle therethrough, of a thread looper movable in a horizontal plane, and a thread hook movable in an upwardly inclined plane with respect to said horizontal plane, said looper and the said thread hook 100 co-operating to positively engage the thread upon the barb of the needle, means for operating the thread looper, said means including a cam-groove wheel, rollers engaging 105 said grooves, one of said rollers being mounted upon a vertically mounted lever and the other of said rollers being mounted upon a longitudinally swinging lever, both of said levers co-operating to impart a differential movement to the said thread looper, an arm mounted for pivotal movement in a vertical plane and operatively connected to the thread hook, and a roller carried by said arm and engaging one of the grooves of said wheel. 110
